WELL PUMPING APPARATUS

Earle Freeman, Dallas, Tex.

Application November 10, 1934, Serial No. 752,391

6 Claims. (Cl. 103—46)

This invention relates to well pumping apparatus and it has particular reference to a stage lift pump.

The principal object of the invention is to provide in a pumping apparatus, a plurality of fluid elevating units collectively operated by a source of electrical energy at the surface, and wherein each of the units is subjected to only a portion of the total fluid head.

Another object of the invention is to provide for the release of gas below each unit level thereby to prevent the gas from interfering with the continuous delivery of liquid by the pumping assembly.

Yet another object of the invention is to provide in one form, a pumping unit wherein the pumping element is itself electromagnetically actuated.

With the foregoing objects as paramount, the invention has particular reference to its salient features of construction and arrangement of parts which will become manifest as the description proceeds, taken in connection with the accompanying drawings, wherein:—

Figure 1 is a vertical section through one of the units embodying one form of pumping element.

Figure 2 is an elevational view partly in section showing the manner in which current is supplied to a unit.

Figure 3 is a continuation of Figure 2 showing the bottom of the assembly.

Figure 4 is a plan view of the unit shown in Figure 1.

Figure 5 is a diagrammatic showing of the electric circuits for supplying current to the form of the invention shown in Figure 1.

Figure 6 is a sectional view of a commutator employed in the distribution of current to the several pumping units.

Figure 7 is a sectional view of an adjacent commutator.

Figure 8 is an elevation in vertical section of another form of the invention.

Figure 9 is an elevational view partly in section of one of the units embodying the structure shown in Figure 8.

Figure 10 is a continuation of Figure 9, and

Figure 11 is a wiring diagram showing the manner for supplying current to the units such as shown in Figure 8.

Continuing with a more detailed description of the drawings, reference is primarily made to Figure 1 in which 1 designates a shell or casing of non-ferrous material whose lower end is in-

teriorly threaded to receive the lower valve casting or plug 2, the latter being likewise comprised of non-ferrous material. Both the shell 1 and the plug 2 are formed to embrace steel inserts 3 which are interiorly threaded to receive the tubing 4.

The plug 2 has a liquid passage 5 therethrough in the base of which reposes a valve cage 6 containing a ball valve 7. Below the valve 7 there is a depending tubular member 8 terminating at 10 a point below an opening 9 in the tubing 4 immediately below the unit. Further reference to this important feature will be made presently.

In the upper part of the shell 1 is a valve seat 10, to which is threadably connected a cage 11 15 in which there is a ball 12.

The principal elements of the pumping mechanism shown in Figure 1 repose within the shell 1, and are comprised of a lifting coil 13, a down stroke coil 14 and a reciprocating plunger or 20 armature 15, which is provided with a central opening 16 as shown. Within the plunger 15 there reposes a valve comprised of a cage 17 and ball 18. The plunger 15 reciprocates within a non-ferrous sleeve 19 and is provided with a 25 groove *a* and a plurality of inwardly extending passageways *b* which communicate with the central opening 16, thereby insuring the removal of sand from around the plunger 15.

Current for energizing the coil 13 is supplied 30 to the unit through insulated lead wires 20, which enter the unit through packing glands 21, while the coil 14 is supplied with current through wires 22 which enter through packing glands 23 as shown in Figure 4. It will be understood that 35 current is supplied alternately to the coil 13 and the coil 14.

It will be noted in Figure 1 that the unit is so designed that when the coil 13 is energized, the plunger 15 is drawn upward by solenoid action 40 and also by the direct magnetic pull of the iron stop 24 upon the plunger. The plunger and stop are best shaped as shown in Figure 1, since a plunger travel of twice the air gap may thus be obtained, thereby minimizing the reluctance of 45 the magnetic path between the stop 24 and the plunger 15. The magnet 13 is provided with an iron casing 25, which forms a path of low reluctance for the flux.

The coil 14 is spaced apart from the coil 13 by 50 a non-ferrous washer 26, and is also provided with a ferrous casing 27 and a stop 28.

One method of supplying current to the coils 13 and 14 alternately is illustrated diagrammatically in Figure 5. Electric power from the line 29 55

serves to drive a motor 30 which is connected to a direct current generator 31. The rate at which current alternates between the coils 13 and the coils 14 of the various units is controlled by a speed changer 32 through which a commutator assembly is driven. This assembly is comprised of a commutator 33, shown in Figure 6, a commutator 34 shown in Figure 7, and a pair of slip rings 35, all suitably mounted upon a shaft and insulated from each other and from the shaft. The commutator 33 is comprised of a relatively large conducting segment 36, while the commutator 34 is provided with a smaller conducting segment 37. This arrangement allows the coils 13 to be energized for longer periods of time than the coils 14, since the coils 13 furnish the pull for the lifting stroke. It will be observed from Figure 5 that the coils 13 of the various units are in parallel, as are the coils 14, current being supplied thereto through lead wires 38. Thus current from the direct current generator 31 first energizes all the coils 13 through the commutator 33 and wire 39, the return path being through wire 40 and one of the slip rings 35. Subsequently the coils 14 are energized for a shorter period of time through commutator 34 and wire 41, the return being through wire 42, after which the cycle is repeated.

In operation, liquid enters a plurality of holes 43 in the pipe 44 and rises under its own head within the pipe 4 and into the deepest pumping unit through pipe 8, any gas within the pipe 4 being free to escape through the opening 9. In order to insure priming, the deepest unit of the system is kept below the fluid level in the well, and to insure efficient operation the various units are arranged to have substantially the same capacity.

Referring to Figure 1, when the coil 13 is energized the plunger 15 is drawn upward by solenoid action and by the magnetic pull between the stop 24 and the plunger. The ball 18 within the cage 17 remains seated, and fluid above the plunger is forced upward. During this upward stroke both the upper ball 12 and the lower ball 7 are raised from their seats within their respective cages by fluid pressure. Subsequently, when the coil 14 is energized, the plunger 15 is drawn downwardly, during which time the plunger ball 18 is raised from its seat and the balls 12 and 7 are seated. As the cycle is repeated fluid is forced upward within the tubing 4.

It is pointed out that because of the limited space within a well, it is virtually impossible to place a single large unit of the type described at the bottom of the hole except in the shallowest of wells, due to the fluid head imposed upon the working element. With the arrangement herein described a plurality of units are arranged at spaced intervals along the tubing, and each unit is subjected to only a fraction of the total fluid head within the well, since the openings 9 in the tubing 4 limit the fluid head on each unit to that existing between that unit and the unit directly above.

Figures 8 to 11 inclusive illustrate a modified form of the invention. In this form electrically driven centrifugal pumps are employed as fluid lifting means, the fluid being elevated by stages along the length of the tubing.

Referring to Figure 8, 45 denotes a housing for an electric motor 46 which is supplied with current through wires 47 which enter the housing 45 through packing glands 48. A ball valve 49 is disposed within a cage 50 which is threaded with 75 in the upper part of the housing 45. A section

of tubing 51 is likewise threaded within the housing 45.

The impeller 52 of the centrifugal pump nearest the motor 46 is keyed to a shaft 53, which is connected to the motor shaft 54 through a coupling 55. The impeller 52 is disposed within a housing 56 which is threaded into the motor housing 45 through a coupling 57. The housing 56 has integral therewith a plurality of deflecting vanes 58 which serve to direct fluid from the impeller 52 upward around the motor 46 and into the space 59.

Fluid pressure serves to lift the valve 49 from its seat within the cage 50, and the fluid is free to pass upward into the tubing 51.

A housing 59 is secured to the housing 56, and has integral therewith deflecting vanes 60, which serve to direct fluid from an impeller 61 upward into the impeller 52. While this form of pumping apparatus has been illustrated with two impellers 60 upon the shaft 53 it is obvious that any number may be employed without departing from the spirit of the invention.

A valve housing 62 is connected to the pump housing 59 and serves to encase a valve cage 63 within which a ball valve 64 is disposed. A pipe 65 serves as a passageway for fluid from the tubing 66 to the units thereabove. This pipe extends downward to a point below a hole 67 in the tubing 66.

In operation, liquid enters a plurality of holes 68 in the pipe 69 and rises under its own head into the deepest of the pumping units, this unit being always immersed in the liquid.

The liquid is forced to the surface by the centrifugal force of the impellers but each of the units along the string of tubing is subject to only its fractional share of the total fluid head, due to the arrangement of the pipes 65 below the units and the holes 67 in the tubing. The various motors 46 are connected in parallel and are driven from a source 70 as shown in Figure 11.

Manifestly, the construction shown is capable of considerable modification and such modification as is considered within the scope and meaning of the appended claims is also considered within the spirit and intent of the invention.

What is claimed is:

1. A pumping apparatus for wells including a tubing within the well, a plurality of pumping units at spaced intervals along said tubing, said tubing having a liquid overflow below and adjacent to each of said pumping units, said units arranged to operate in series; each of said units being arranged to deliver liquid to the unit thereabove and each of said units being provided with a pump pick-up within said tubing, said pick-up terminating at a point below the liquid overflow of the adjacent lower unit.

2. A pumping apparatus for wells including a tubing within the well, individually driven pumping units at spaced intervals along said tubing, said tubing having a liquid outlet below and adjacent to each of said pumping units, said units arranged to operate in series; each of said units being arranged to deliver liquid to the adjacent higher unit, and each of said units provided with an intake pipe within said tubing, said pipe terminating at a point below the liquid outlet of the adjacent lower unit.

3. A pumping apparatus for wells including a tubing within the well, magnetically actuated pumping units at spaced intervals along said tubing, said tubing having a liquid overflow below each of said pumping units, said units ar- 75

5 ranged to operate in series, each of said units being arranged to deliver liquid to the adjacent higher unit, and each of said units provided with a liquid intake, said intake extending within said tubing below the adjacent liquid overflow.

10 4. A well pump including a tubing, individually driven and electromagnetically actuated pumping units at spaced intervals along said tubing, said tubing having a liquid overflow below each of said pumping units, said units arranged to operate in series, each of said units being arranged to deliver liquid to the adjacent high unit, and each of said units provided with a liquid intake extending within said tubing below the adjacent liquid overflow.

15 5. A pumping apparatus for wells including a tubing within the well, a plurality of centrifugal pumping units at spaced intervals along said tubing, said tubing having a liquid overflow below

each of said pumping units, said units arranged to operate in series, each unit delivering liquid to the unit thereabove and each of said units provided with a liquid intake extending within said tubing below the adjacent liquid overflow.

6. A pumping apparatus for wells including a tubing within said well, individually driven centrifugal pumping units at spaced intervals along said tubing, said tubing provided with a liquid overflow adjacent to and below each of said pumping units, whereby to subject each of said units to a fractional part of the total fluid head and to exclude gas from each of said units, said units being arranged to operate in series, each unit delivering liquid to the unit thereabove, and each of said units provided with a liquid intake extending within said tubing and terminating below the adjacent liquid overflow.
